M. W. SEWALL.
TRAVELING GRATE.
APPLICATION FILED FEB. 3, 1913.

1,200,247.

Patented Oct. 3, 1916.

UNITED STATES PATENT OFFICE.

MINOTT W. SEWALL, OF NEW YORK, N. Y., ASSIGNOR TO THE BABCOCK & WILCOX COMPANY, OF BAYONNE, NEW JERSEY, A CORPORATION OF NEW JERSEY.

TRAVELING GRATE.

1,200,247.

Specification of Letters Patent.

Patented Oct. 3, 1916.

Application filed February 3, 1913. Serial No. 745,807.

To all whom it may concern:

Be it known that I, MINOTT W. SEWALL, a citizen of the United States, residing at New York city, borough of Manhattan, in the county of New York and State of New York, have invented certain new and useful Improvements in Traveling Grates, of which the following is a specification:

My invention relates to traveling grates. As at present built, chain or traveling grates are usually mounted on a frame carried on wheels to enable the whole structure to be withdrawn from the furnace, in order that the repairs may be made to it. This has the advantage of making all parts accessible, or, if it is drawn only part way, of making such part of it accessible as is withdrawn. Among the disadvantages attending the usual construction may be enumerated the following: (1) The stoker parts are inaccessible when in place for operation; (2) If the stoker be a long one, great width of fire room is required; (3) The stoker frame, together with the supporting rail beams and pit between them, involve considerable expense; (4) There is a difficulty in replacing links due to the long link rods, especially if the boilers be in battery without excessively thick center walls; (5) The necessary conservation hoppers are expensive to the customer, outside of the stoker costs; (6) A broken link sometimes breaks another part of the stoker before it is discovered or replaced; (7) The driving parts if properly protected from fire room dust are expensive; (8) The driving rig is mounted on the stoker frame and therefore must be easily detachable from the driving parts common to all of the stokers in the boiler plant or unit.

The object of the present invention is to overcome, so far as may be, the above mentioned disadvantages, and will be understood by reference to the accompanying drawings in which—

Figure 1 is a vertical longitudinal section of a furnace and traveling grate; Fig. 2, a transverse section on the plane of the line 2—2 of Fig. 1; Fig. 3, a transverse section on the plane of the line 3—3 of Fig. 1; and Fig. 4, a partial sectional plan on the plane of the line 4—4 of Fig. 1.

Similar reference numerals indicate similar parts in the several views.

Referring to the drawings the numeral 1

designates the furnace space of a steam boiler in which the grate is placed, sufficient parts of the side walls and of the boiler setting being shown to facilitate an understanding of the application of the present invention. The lower side walls of the furnace are protected by a water cooling system described in my application Serial No. 699,860, filed May 27, 1912, this system comprising side water tubes 2 and side water boxes 3. Cross boxes 4 and 5 form the bridge wall of the furnace, said tubes and boxes being connected with the boiler circulation.

The traveling grate which I have shown for the purpose of describing my invention consists of a grate surface made up of interlocking links 6 held in position by rods 7. Short link rods may be used which can be driven out into the space under the center wall by working in the passage way, enabling all links to be replaced or the drag way instead of in front if preferred.

The fuel support consists of an endless web or belt passing around sprocket wheels 8 and 9, said wheels being mounted on shafts supported in suitable bearings. Fig. 3 shows the rear sprocket shaft 10 with one of its bearings 11. A screw jack 12 may be used for raising or lowering the shaft, the lower bearing of said jack resting on the floor. The front sprocket shaft is carried in fixed supports and is placed high enough above the floor to allow the worm to be installed below the wheel, giving an arrangement by which the worm may be partially immersed in oil, thus providing for continuous lubrication in a simple manner, and an arrangement of parts that may be enclosed by a simple and inexpensive plate 95 metal covering.

The upper or forward run of the grate is supported upon rollers 13 carried on rods 14, said rods being supported at their ends in bars 15, the latter being notched on their upper edges to receive the rods. The bars 15 are attached to vertical supports 16 and these in turn are secured through plates 17 to vertical supports 18, which latter are the supports for the boiler casing plates. By 105 this construction side walls below the grate line are not required, plates installed for closing the space in, being substituted.

The side water boxes 3 are spaced apart at least the distance of the width of the grate, 110

and the bottoms of the boxes are slightly above the upper surface of the grate. As shown in Figs. 2 and 3 these boxes are partially supported upon angle bars 25 secured 5 to the vertical supports 16, said bars extending longitudinally along the sides of the grate links and serving to close the air space between the grate and the side water boxes.

For the lower or return run of the grate 10 I provide a floor 19 independent of the grate structure and upon which the return run rests as it is drawn to the front of the furnace. As shown in Fig. 1 the lower or return run of the grate between the sprockets 15 is longer than the upper or forward run of the grate between the sprockets so as to sag and conform to the shape of the floor over which it travels. This floor may be constructed in any suitable manner and of suitable 20 material, such as concrete or with a surface of concrete or similar building stuff, and is a part of the building structure, that is, it constitutes the furnace floor and is prepared as a part of the installation and is independent of the grate structure. It may lie in a horizontal plane, or may be inclined downwardly or upwardly from the rear to the front. As shown it begins a short distance in front of the rear sprocket wheels 25 and terminates near the front of the furnace opening. Its width is substantially that of the grate. To prevent undue wear of the floor I may embed therein metal strips 20. As the return run rests directly upon the floor I may install anti-friction wheels 21 built into the floor to reduce the friction.

Below the forward or discharge end of the floor 19 is a belt or other carrier 22 for conveying the siftings brought forward by 40 the return run of the grate, these siftings falling through the upper run of the grate upon the floor.

From the foregoing description it will be seen that the usual practice of removing the 45 stoker from under the boiler for repairs has been abandoned, there being sufficient space between the upper and lower runs of the chain allowed for a man to enter for access

to all parts of the interior of the stoker, and to the inner ends of the rear shafts when a 50 battery setting is used, by entering the space between the stokers under the center wall of the battery.

A shield 23 prevents refuse from falling under the rear end of the grate and directs 55 it to an auxiliary grate 24.

What I claim and desire to secure by Letters Patent of the United States is:—

1. A traveling grate having a fuel-supporting surface, sprocket wheels around 60 which the grate travels, and a supporting floor for the lower or return run, the lower or return run of the grate between the sprockets being longer than the upper or forward run of the grate between the sprockets 65 so as to sag and conform to the shape of the floor over which it travels.

2. A traveling grate having a fuel-supporting surface, sprocket wheels around 70 which the grate travels, and a supporting floor for the lower or return run, said floor sloping upward from the rear to the front, the lower or return run of the grate between the sprockets being longer than the upper or forward run of the grate between the 75 sprockets so as to sag and conform to the shape of the floor over which it travels.

3. A traveling grate having a fuel-supporting surface, sprocket wheels around 80 which the grate travels, a supporting floor for the lower or return run, said floor sloping upward from the rear to the front and having metallic wear members, the lower or return run of the grate between the sprockets being longer than the upper or forward 85 run of the grate between the sprockets so as to sag and conform to the shape of the floor over which it travels.

In testimony whereof I have hereunto signed my name in the presence of two sub- 90 scribing witnesses.

MINOTT W. SEWALL.

Witnesses:

J. E. BELL,
JOHN A. W. DIXON.
